United States Patent Office

Des. 200,946
Patented Apr. 20, 1965

200,946

BICYCLE

Alexander Eric Moulton, Bradford-on-Avon, England,
assignor to Moulton Consultants Limited, a company
of Great Britain

Filed May 1, 1964, Ser. No. 79,898

Claims priority, application Great Britain Oct. 16, 1962

Term of patent 14 years

(Cl. D90—8)

FIG. 1.

FIG. 2.

Des. 200,946

PAGE 2

FIG. 3.

FIG. 4.

FIG.5.

FIG.6.

FIG. 7.

FIG. 1 is a front perspective of the bicycle showing my new design.

FIG. 2 is a rear perspective.

FIG. 3 is a side elevation.

FIG. 4 is an elevation of the side opposite that shown in FIG. 3.

FIG. 5 is a front perspective of a modified form.

FIG. 6 is a rear perspective of the modified form; and

FIG. 7 is a side elevation of the modified form.

The dominant features of my design reside in the portions shown in full lines.

This application is a continuation-in-part of my application Serial D. 73,212, filed January 17, 1963, and now abandoned.

I claim:

The ornamental design for a bicycle, as shown and described.
